UNITED STATES PATENT OFFICE.

JAMES McCARTHY, OF NORWICH, CONNECTICUT.

BLIND-FASTENER.

SPECIFICATION forming part of Letters Patent No. 532,805, dated January 22, 1895.

Application filed April 19, 1894. Serial No. 508,116. (No model.)

To all whom it may concern:

Be it known that I, JAMES McCARTHY, a citizen of the United States, residing at Norwich, county of New London, State of Connecticut, have made certain new and useful 5 Improvements in Blind-Fasteners, which improvements are fully set forth and described in the following specification, reference being had to the accompanying sheet of drawings.

10 This invention is in a well known class of blind fasteners now in common use, consisting of a spring pressed lever pivotally hung in the blind, each end of which lever is formed as a hook, one of said hooks coacting with a 15 staple driven or screwed into the window sill to retain the blind in its closed position and the other end of said lever likewise coacting with a staple or screw-eye secured to the wall of a building to retain the blind in its open 20 position.

While fasteners of this class serve satisfactorily to lock the blind open or closed they (as now constructed) do not prevent the interlocking parts from vibrating and rattling 25 when moved by the wind.

The object of this invention is to overcome the objectionable feature described above by so constructing a fastener that when a blind is locked thereby in its open position no vibrating movement of the same will be possible. This desirable object is accomplished 30 by improving the said screw eye but in such manner that the same will coact as readily as heretofore with the double hook-lever, a detailed description of which hook-lever is 35 deemed unnecessary for the reason that its construction is identical with the form now in common use and is well known.

To assist in explaining my invention I have 40 provided the accompanying drawings, in which—

Figure 1 illustrates in elevation my improved blind-fastener as the same appears when in use. Fig. 2 is a view partly in section showing the preferred means provided in connection with the screw-eye for preventing vibration of the blind. Fig. 3 embraces side and edge views of a screw-eye fitted up with a modification of my invention.

50 Referring to the drawings the letter *a* indicates the usual lever-hook provided in this class of blind fasteners and *b* the screw-eye

secured to the side of the building in connection with which hook-lever *a* operates when serving to hold the blind open. Screw-eye *b* 55 is provided with a cylindrical portion *c* located at one side of the eye proper, which is bored to provide a chamber *d* to receive a bolt *e*. In chamber *d* is placed a spiral spring *f* one end of which abuts the bottom of the 60 chamber and the opposite end the inner end of the bolt *e*, which spring by reason of its expansive tendency seeks ever to force bolt *e* out of its chamber but is prevented from so doing by reason of a pin *g* extending across 65 chamber *d* at right angles to bolt *e*, a depression *e'* being provided throughout a portion of the bolt *e* to receive said pin, as shown in Fig. 2.

With a screw-eye of the above described 70 construction properly secured to the side of a house it will be seen that in the operation of locking a blind in its open position, said blind as it approaches the screw-eye will first 75 come in contact with bolt *e* which latter will be pushed before it into the chamber *d* against the force of its spring *f* until the hook-lever *a* snaps into the screw-eye in the usual manner. The spring *f* then serves to crowd the lever-hook tightly against the inner wall of the 80 screw-eye thus taking up all play or undue movement of the locking parts and making it impossible for them to rattle.

Fig. 3 illustrates a modification of my invention such modification consisting in providing the ordinary screw-eye with a metallic spring *h* extending from the head *b'* of such screw eye to a point somewhat beyond the outer end of the same, said spring being secured to the screw-eye in any suitable manner. Spring *h* serves to engage the blind with a tendency to force the same outward when closed, in the same manner as the bolt already described, thereby taking up the play between the screw-eye and the hook. 95

My invention may be very cheaply produced, is very simple in its construction and accomplishes effectually the object for which it was intended.

Having described my invention, I claim— 100

1. As an article of manufacture, a screw-eye having combined therewith a spring actuated buffer, the outer end of the buffer extending beyond the end of the eye, whereby

it will engage with the blind and be forced inward when the hook on the blind engages with the eye substantially as and for the purpose specified.

- 5 2. As an article of manufacture, a screw eye having a hollow cylindrical portion at one side thereof, a spring-actuated buffer seated within the said hollow portion, the outer end of which projects beyond the outer end of the eye, and means for preventing the escape of the buffer, substantially as set forth.
- 10 3. As an article of manufacture, a screw

eye having a hollow cylindrical portion at one side thereof, a spring-actuated recessed bolt or buffer within said hollow portion, the outer end of which projects beyond the outer end of the eye, and a pin extending through the cylindrical portion of the eye and within the recessed portion of the bolt, substantially as set forth.

JAMES McCARTHY.
